DESIGN FOR AN AIRPLANE

Athanas P. Fontaine, San Marino, and Charles R. Irvine, Whittier, Calif., assignors to Consolidated Vultee Aircraft Corporation, San Diego, Calif., a corporation of Delaware

Application August 3, 1944, Serial No. 114,719

Term of patent 14 years

(Cl. D71—1)

To all whom it may concern:

Be it known that we, Athanas P. Fontaine, a citizen of the United States, residing at San Marino, in the county of Los Angeles and State of California, and Charles R. Irvine, a citizen of the United States, residing at Whittier, in the county of Los Angeles and State of California, have invented a new, original, and ornamental Design for an Airplane, of which the following is a specification, reference being had to the accompanying drawings forming part thereof, wherein

Figure 1 is a top plan view of an airplane showing our new design;

Figure 2 is a front elevational view;

Figure 3 is a side elevational view; and

Figure 4 is a perspective view showing the airplane in flight.

We claim:

The ornamental design for an airplane, substantially as shown.

ATHANAS P. FONTAINE.
CHARLES R. IRVINE.
